UNITED STATES PATENT OFFICE

JOHN B. ZALLIO, OF CHICAGO, ILLINOIS

DISH COVER

Application filed August 13, 1927. Serial No. 212,742.

My invention has for its general objects the provision of a dish cover which is adapted to permit the stacking of food laden dishes with comparative safety and which retards the transmission of heat between the stacked dishes, so that the food on the dishes will remain hot or cold as the case may be for a comparatively long period with obvious advantage particularly in restaurant service where some time generally elapses between the placing of the food on the service plates and the serving of the patrons therewith.

With these objects in view my invention consists in certain features of novelty in the construction, combination, and arrangement of parts by which the said objects and certain other objects, hereinafter appearing, are effected, all as fully described with reference to the accompanying drawing and more particularly pointed out in the appended claims.

In the said drawing—

Figure 1 is a bottom plan view of a dish cover embodying my invention;

Figure 2 is a side elevation of the same with parts thereof broken away and in section;

Figures 3 and 4 are enlarged partial sections of different portions of the dish cover on the line 2—2 of Figure 1.

Like characters of reference indicate like parts in the several views.

Referring to the drawing, 1 designates a cup shaped body, preferably formed of suitable sheet metal such as aluminum. See Figures 1 and 2. The transverse wall of the body is provided with a circular marginal inset 2 forming a circular marginal exteriorly facing groove 3, and the central portion 4 of said transverse wall is disposed in a plane intermediate the plane of the extreme margin 5 of this wall and the plane of the bottom of the groove 3. The central portion 4 of the transverse wall of the body is provided with apertures 6 spaced about the axis of the body and disposed adjacent the groove 3, and engaged in said apertures are circumferentially grooved rubber bushings 7 which project exteriorly of said transverse wall to a plane between the planes of the extreme

margin 5 and the central portion 4 of said transverse wall. See Figures 1, 2, and 4.

The outer ends of the bushings 7 provide support means of restricted area adapted to be engaged by the central bottom surface of a service plate 8, see Figure 2, to support this plate above the body 1 in spaced relation therewith, the groove 3 providing clearance for the usual circular rib 9 on the bottom of the plate. Thus, as the plate 8 is thus supported on the body 1, air space is provided between the plate and the body 1 so that heat transmission therebetween is effectively retarded. The engagement of the rubber bushings 7 with the bottom of the service plate 8 prevents slipping of the plate to a great extent, and the extreme margin 5 of the transverse wall of the body serves to prevent the plate from being laterally dislocated with respect to the body 1.

In addition the marginal groove 3 provides a convenient hand hold on the cover, particularly for placing the cover on and removing it from a service plate, the portions of the circumferential wall of the body and the groove 3 adjacent the extreme margin 5 of the transverse wall forming a marginal exterior ridge formation which may be grasped by the fingers of the user's hand.

The body 1 is provided at the bottom opening thereof with a continuous circular marginal groove formation 11 facing inwardly in the direction of the plane of said opening, and engaged exteriorly in this groove is a continuous circular tubular metal member 12 having a continuous longitudinal slit 13 in the wall thereof forming an undercut groove facing outwardly of said opening of the body 1. See Figures 1, 2, and 3. A rubber contact strip is provided and has a relatively thick longitudinal portion 14 engaged in the groove of the tubular member 12 and a relatively thin longitudinal portion 15 projecting outwardly from this groove through the slit 13 to contact the marginal portion of the upper surface of a second service plate 16 upon which the cover is placed for enclosing the food on this plate. See Figure 2. This contact strip in its engagement with the plate 16 prevents slippage to a great extent, and it will be ob-

served that the structure by which the contact strip is mounted on the body 1 adequately secures the contact strip with the body and is particularly adapted to a sheet metal structure as shown.

5 In Figure 2 but two service plates are shown in stacked relation with one dish cover, it being apparent that any reasonable number of service plates covered with dish covers of 10 my invention may be stacked with reasonable safety.

While I have herein shown and particularly described the preferred embodiment of my invention I do not wish to be limited to the 15 precise details of construction shown as changes may readily be made without departing from the spirit of my invention, but having thus described my invention I claim as new and desire to secure by Letters Patent the following:—

20 1. In an article of the character described the combination with a cup shaped body provided with a circular exteriorly facing marginal groove on the transverse wall thereof, of support means of restricted area on said transverse wall and disposed inwardly of 25 said groove and projecting exteriorly.

2. In an article of the character described the combination with a cup shaped body provided with a circular exteriorly facing marginal groove on the transverse wall thereof and provided with apertures in said transverse wall disposed inwardly of said groove and spaced about the axis of the body, of 35 rubber support members secured in said apertures and projecting exteriorly of said wall.

3. In an article of the character described the combination with a cup shaped sheet metal body provided with a circular marginal 40 inset on the transverse wall thereof forming a circular exteriorly facing marginal groove on said transverse wall and having the central portion of said wall disposed in a plane 45 intermediate the plane of the extreme margin of said wall and the plane of the bottom of said groove and having said central portion of said wall provided with apertures spaced about the axis of the body and disposed adjacent said groove, of circumferentially grooved rubber bushings engaged in 50 said apertures and projecting exteriorly of said wall to a plane between the planes of said central portion and the extreme margin 55 of said wall.

4. In an article of the character described the combination with a hollow sheet metal body provided with an opening and having a marginal groove formation at said opening 60 and facing in the direction of the plane of said opening, of a tubular metal member engaged exteriorly in said groove and having a longitudinal slit in the wall thereof forming an undercut groove facing outwardly of 65 said opening, and a rubber contact strip hav-

ing a relatively thick longitudinal portion engaged in the groove of said tubular member and having a relatively thin longitudinal portion projecting outwardly of this groove through said slit.

5. In an article of the character described the combination with a hollow sheet metal body provided with a circular opening and having a continuous circular marginal groove formation at said opening and facing inwardly in the direction of the plane of said opening, of a continuous circular tubular metal member engaged exteriorly in said groove and having a continuous longitudinal slit in the wall thereof forming an undercut 80 groove facing outwardly of said opening, and a rubber contact strip having a relatively thick longitudinal portion engaged in the groove of said tubular member and having a relatively thin longitudinal portion projecting outwardly of this groove through said slit.

In witness whereof I hereunto affix my signature this 12th day of July, 1927.

JOHN B. ZALLIO.
